UNITED STATES PATENT OFFICE.

LOUIS O. OXENDORF, OF MILWAUKEE, WISCONSIN.

SWINGING BED.

Application filed July 10, 1924. Serial No. 725,166.

To all whom it may concern:

Be it known that I, LOUIS O. OXENDORF, a citizen of the United States, residing at Milwaukee, in the county of Milwaukee and State of Wisconsin, have invented certain new and useful Improvements in Swinging Beds, of which the following is a specification.

This invention relates to swinging bed structures especially adapted to be used upon ships, and it consists in the novel features hereinafter described and claimed.

An object of the invention is to provide a bed structure of the character stated, which is preferably made of metal and including four posts, with means for securing the ends of the posts to the upper and lower deck surfaces or floor of one deck and ceiling of the next deck. U-shaped brackets are interposed between the posts and are located at the end of the bed structure and bars are supported at the intermediate portions of the said brackets and couches are connected by means of links with the said bars, whereby the said couches may swing and remain in horizontal position as the said posts rock with the decks.

Hook members are provided for fixing the couches with relation to the posts when desired.

In the accompanying drawing:

Figure 1 is a side elevational view of the swinging bed structure, with one of the posts broken away, and parts of the structure shown in section.

Figure 2 is an end elevational view of the swinging bed structure.

The swinging bed structure comprises posts 1, having plates 2 applied to the ends thereof, and the said posts are erected between the decks indicated at 3 and 4. Inverted U-shaped brackets 5 are interposed between the posts 1, at the ends of the bed structure, and are secured to the said post by means of bolts 6, which pass transversely through the end portions of the said

brackets and the said post. Bars 7 are supported upon the intermediate portions of the brackets 5 and are held by means of cotter means 8, which pass transversely through the said bars and the intermediate portions of the bracket. Chain links 9 depend from the end portions of the bar 7, and support couch structures 10, whereby said structures may swing and remain horizontal as the posts rock with the decks 3 and 4. The couches 4 are provided at their lower side portions with eyes 11, into which hooks 12 may be engaged. The said hooks are pivotally supported upon the post 1. When the hooks 12 are engaged in the eyes 11, the couches 10 are practically fixed with relation to the post 1, and are held against relative swinging movement.

From the foregoing description, taken in conjunction with the accompanying drawing, it will be seen that a swinging bed structure of simple and durable arrangement is provided, and that the structure may be conveniently used upon ships to support the bed couches in horizontal position, while the ship is rocked.

Having described the invention, what is claimed is:

A swinging bed structure comprising posts, bolts, plates applied to the ends of the posts, inverted U-shaped brackets applied to the posts at the ends of the bed structure, bars mounted upon the intermediate portions of the bracket members and disposed longitudinally of the bed structure, means for fixing the bars to the bracket members, links hanging pendant from the end portions of the bar, couches supported by the links and located between the posts, and hooks mounted upon the posts and engageable with the couches, to hold the couches stationary with relation to the posts.

In testimony whereof I affix my signature.

LOUIS O. OXENDORF.
